United States Patent

Des. 235,257
Patented June 3, 1975

235,257

CARD FILE OR SIMILAR ARTICLE

Gordon Perry, Bayside, N.Y., assignor to Oxford
Pendaflex Corporation, Garden City, N.Y.

Filed July 25, 1973, Ser. No. 382,484

Term of patent 14 years

Int. Cl. D19—02

U.S. Cl. D19—76

FIG. 1 is a perspective view of a card file or similar article showing my new design;

FIG. 2 is a top plan view;

FIG. 3 is a front elevational view;

FIG. 4 is a right side elevational view;

FIG. 5 is a bottom plan view; and

FIG. 6 is a rear elevational view.

I claim:

The ornamental design for a card file or similar article, as shown and described.
